ELEVATOR FOR SHEET FEEDERS

Leonard Baker, Hillsdale, N. J., and Leo C. Williams, Pearl River, N. Y., assignors to Dexter Folder Company, Pearl River, N. Y., a corporation of New York

Application June 25, 1942, Serial No. 448,386

23 Claims. (Cl. 271—62)

The invention relates to an elevator for a sheet feeder. A pile of sheets such as paper are loaded upon the elevator and the top sheet is removed therefrom by suitable sheet feeding devices. The elevator is slowly, or intermittently, raised as the sheets are taken off of the top of the pile. The invention relates particularly to the elevator mechanism whereby, when the pile of sheets have been removed from one elevator platform, the latter is withdrawn and elevator side bars are rapidly dropped which automatically engage a second platform upon which there is a second pile of sheets ready to be raised to sheet feeding position. This construction permits the sheet feeder to be rapidly supplied with another pile of sheets so that the feeder is not out of service for too long a time.

It is an object of the invention to construct a new and novel elevator mechanism which has a platform which is removable when the pile of sheets thereon have been removed and so constructed that the platform raising mechanism may be rapidly dropped to its bottom position, whereupon, the second platform already in position at the bottom of the elevator and loaded with a pile of sheets may be engaged and raised to sheet feeding position.

Another object of the invention is to construct a locating arrangement for the platform upon which the sheets are piled so that it is in proper position to be engaged by the elevating mechanism.

Another object is to construct a new and novel elevator utilizing a removable platform which is placed in position at the bottom of the elevator whereupon, the elevating mechanism automatically engages the platform so that it may be raised into sheet feeding position.

Another still further object is to construct a new and novel elevator platform for a sheet feeder elevator.

Another object is to provide a new and novel mechanism for removing a platform from the elevator.

Other objects of the invention will be more apparent from the following description taken in connection with the accompanying drawings which illustrate a preferred embodiment of the invention in which:

Figure 1 is a side elevation of the sheet feeder elevator with part of the frame in section showing an elevator platform and side bars in partially raised position and with a second platform at the bottom of the elevator in its initial posi-

tion prior to shifting the same forward into final position.

Figure 2 is a vertical section of the elevator taken on line 2—2 of Figure 1 and shows one platform adjacent the top of the elevator and a second platform at the bottom thereof in position to be engaged by the side bars when they are dropped to the bottom of the elevator.

Figure 3 is a horizontal section taken on line 3—3 of Figure 1 and shows the partially raised platform of Figure 1 and underneath the partially raised platform is shown the second platform at the bottom of the elevator in initial or first position.

Figure 4 is a view of part of the elevator guides, a side bar and the removable platform with the latter tilted for removal from the side bars.

Figure 5 is a partial view of the bottom of the elevator showing a platform in final position ready to be engaged by the side bars and the mechanism for supporting and locating the platform in proper position.

Figure 6 is an enlarged view of a retractile latch carried by the elevator platform with the latch being engaged by a side bar to retract the same and permit the bar to pass therebeneath.

Figure 7 is another enlarged view showing the latch extended and engaged by the top of the side bar preparatory to raising the platform.

Figure 8 is an enlarged view of the platform showing adjustable extension members carried thereby.

The elevator and sheet feeder are mounted upon or attached to a machine to which sheets are to be fed and in the embodiment illustrated, are mounted upon a printer frame to which the sheet feeder feeds the sheets from the elevator. The frame for the elevator is preferably formed from two spaced rectangular sides, each side comprising a pair of spaced walls 11 and 12. Each pair of spaced walls provide an elevator guide for a side bar 13 and hence there are two such side bars. The sides of each rectangular wall provide guiding edges which are spaced apart wide enough to pass a platform therebetween as will appear more fully hereinafter. Each side bar carries a suitable roller 14 at each end thereof to engage the edge of its respective guide and is thereby retained in position between the spaced walls 11 and 12. A rod 15 extends between each side bar and is secured thereto at a point adjacent the rear ends of the side bars.

The side bars 13 are raised by suitable mechanism, that particularly illustrated comprising a cable 18 for each side bar which is secured to

one end of its respective side bar and passes over the sheaves 19 and 20 to a winding drum 21. A second cable 22 is provided for each side bar which is attached to the other end of its respective bar and passes over the sheave 20 and to the winding drum 21. The winding drum is rotated by suitable driving mechanism enclosed in the gear box 23 (Figure 2). A clutch mechanism is included with the driving mechanism which may be released, whereupon the side bars 13 descend of their own weight. The purpose of the clutch mechanism is to disconnect the winding drum 21 from the driving mechanism so that the side bars may be quickly dropped to the bottom of the elevator to pick up a second platform which has been loaded with a pile of sheets to be raised to sheet feeding position.

The elevator includes a platform upon which a pile of sheets is stacked. The platform includes a pair of cross bars 26, shown as channel irons or bars, which are secured in spaced relation by angle irons 27 forming cross braces. A deck 28 is secured to the platform frame formed by the channel irons or cross bars and the cross braces. Each cross bar, Figure 6, has a plate 29 secured such as by welding to the edges of the flanges of the channel irons at each end thereof so as to form latch housings. A pivot pin 30 passes through the web of the cross bar 26 and each plate 29 upon which pin a latch 31 is pivotally mounted. Each latch has a camming surface 32 and a notch 33 so that the lower edge of the respective descending side bar 13 engages the camming surface to retract the latch. When the side bar 13 has dropped below the latch, the latter swings to normal extended position so that the notch 33 is in position to engage the top edge of its respective side bar as it is raised to elevate the platform and pile of sheets stacked thereupon. By engaging the top edge of the flat side bar the weight of the platform and its load is in alignment with the side bar guides.

The latch carries an inwardly directed extension 34 which counterbalances the latch and serves to restore the latch to its normal extended position as shown in Figure 7. The extension also serves as a stop when it engages the lower flange of the channel iron or cross bar 26 as shown in Figure 7 to hold the latch extended and from swinging upwardly when it is supporting the weight of the platform. The extension also serves as a stop against too far a rotation in a clock-wise or retracting direction by engaging the top flange of the channel iron or cross bar.

The platform described with a pile of sheets thereon is raised on the pair of side bars 13 to sheet delivery position and then is raised slowly or intermittently until the sheet feeder has removed all, or substantially all of the sheets therefrom. The platform is then lowered to bring it well clear of the frame or guide so that it may be removed from the side bars through the side of the frame, whereupon, the clutch is released and the side bars drop down to the bottom of the elevator. Each latch 31 upon each end of the two cross bars 26 is cammed to retracted position by the falling side bars 13. When the side bars descend to their lower position, which is lower than the latches, the latter move into extended position above the side bar as illustrated in Figure 7. Engagement of the clutch raises the two side bars 13 so that each top surface thereof engages their respective latches 31 and raises the platform with its pile of sheets thereon to sheet feeding position.

The platform preferably has adjustable means at one edge thereof for extending the platform or the deck thereof along one side so that the whole or substantially whole lower surface of the pile of sheets which extend between pile guides 37 is supported. The pile guides are carried in suitable fashion by the frame and, in the illustrated embodiment, they are adjustable laterally upon a supporting bar 38, Figure 2, carried by the frame. The adjustable means for the platform or deck includes a bar 39 shown in Figure 8 which is secured to and spaced from the forward edge of the platform or deck or particularly the cross bar 26 by any suitable means such as the bolts 40 and spacing washers 43. The adjustable means includes a plurality of angle members 41 which have a spring 42 attached to one side thereof. The spring side of the angle members is projected between the spaced bar 39 and the edge of the platform, or particularly between the edge of the deck 28 and the face of the channel iron 26, to frictionally retain the same in position. A series of such angle members are used as illustrated in Figure 3. They may be moved laterally along the edge of the platform or may be removed entirely in case the sheet upon the platform is a short sheet.

One of the channel cross bars 26 preferably carries a roller 45 near the far edge of the platform for ease in removing the same from the side bars 13 of the elevator. In removing the platform it is lowered, for example to the position shown in Figure 1, and pulled towards the rear, that is, to the right as illustrated in this figure, so that the angle members 41 are clear of the pile guides 37 whereupon the platform may be tilted, as shown in Figure 4, or pulled out laterally in level position to bring the roller 45 into engagement with the roller bar 15. The attendant standing at the near side, which would be at the bottom as viewed in Figure 3, then raises the near side of the platform to bring the plate 29 and channel 26 above the near side bar 13 after which the platform is drawn toward the attendant and removed through the side of the elevator with the roller 45 rolling along the bar 15.

Means are provided to locate the platform in proper position at the bottom of the elevator. This means includes a pair of supports 47 preferably made of angle irons so that a pair of spaced upstanding flanges 48 and 49 are provided. These supports are secured to the frame in any suitable fashion, such as by the blocks 50, Figure 7, having bolts 51 which secure the blocks to the side wall 12 and bolts 52 which secure the supports to the blocks 50. The platform is inserted through the side of the frame into the elevator so that the bottom of the legs formed by the plates 29 rest upon the horizontal portion of the angle irons or supports 47. The edges of the plates 29 engage the side walls 12 to position the platform in a lateral direction. For forward and rearward position, one pair of plates 29, which are secured to the inner edges of the channel irons 26, engages the upstanding flange 48 as a locating stop for the initial or rearward position of the platform. The platform is then pushed forward or to the left as viewed in Figure 1 until the other pair of plates 29 carried by the right-hand cross bar 26, as viewed in Figure 5, engages the upstanding flange 49 whereupon the platform is located in proper position to be elevated. In this position 75 of the platform the adjustable extensions 41 ex-

tend between the pile guides 37 as viewed in Figures 3 and 5.

This invention provides an improvement in an elevator for sheet feeder. It is understood that various modifications in structure, as well as changes in mode of operation, assembly, and manner of use, may and often do occur to those skilled in the art, especially after benefiting from the teachings of an invention. This disclosure illustrates the preferred means of embodying the invention in useful form.

What is claimed is:

1. A sheet feeder elevator comprising a pair of spaced guides, a side bar guided by each spaced guide, means to elevate the side bars, a platform for supporting a pile of sheets to be raised to feeding level, retractile latches carried by the platform which retract by engagement with the descending side bars and thereafter extend to be engaged by the rising side bars at a point in alignment with the guides to lift the platform and a pile of sheets, and means adjacent the bottom of the spaced guides to locate the platform in position for engagement of the latches of the latter by the side bars for raising the platform.

2. A sheet feeder elevator comprising a pair of spaced guides, a side bar guided by each spaced guide, means to elevate the side bars, a platform for supporting a pile of sheets to be raised to feeding level, retractile latches carried by the platform which retract by engagement with the descending side bars and thereafter extend to be engaged by the rising side bars to lift the platform and pile of sheets, and a pair of upwardly extending and spaced flanges adjacent the bottom of the spaced guides to locate the platform in two positions prior to engagement of the latches of the latter by the side bars for raising the platform, one of said flanges forming a forward stop and the other a rear stop for the platform.

3. A sheet feeder elevator comprising a pair of spaced guides, a side bar guided by each spaced guide, means to elevate the side bars, a platform for supporting a pile of sheets to be raised to feeding level, retractile latches carried by the platform which retract by engagement with the descending side bars and thereafter extend to be engaged by the rising side bars to lift the platform and pile of sheets, and a pair of spaced angle irons adjacent the bottom of the spaced guides having one upwardly extending flange upon one angle iron forming a forward stop and the upwardly extending flange upon the other angle iron forming a rear stop to locate the platform in two positions prior to engagement of the latches by the side bars for raising the platform, the platform resting upon the horizontal sides of the angle irons.

4. A sheet feeder elevator comprising a pair of spaced guides; a side bar guided by each spaced guide; means to elevate the side bars; a platform for supporting a pile of sheets to be raised to feeding level including a pair of spaced channel irons, a plate secured to the flanges at each end of the channel irons forming a latch housing, a retractile latch carried in each latch housing and normally projecting therefrom which retracts by engagement with the descending side bars and thereafter extends to be engaged by the rising side bars to lift the platform and pile of sheets and a deck upon the channel irons; and means adjacent the bottom of the spaced guides to locate the platform in position for engagement

of the latches of the latter by the side bars for raising the platform.

5. A sheet feeder elevator comprising a pair of spaced guides; a side bar guided by each spaced guide; means to elevate the side bars; a platform for supporting a pile of sheets to be raised to feeding level including a pair of spaced channel bars, a plate secured to the flanges at each end of the channel bars forming a latch housing, a pivoted retractile latch carried in each latch housing which retracts by engagement with the descending side bars and thereafter extends to be engaged by the rising side bars to lift the platform and pile of sheets, each latch having an inwardly directed extension which engages the flanges as a stop, and a deck carried upon the channel irons; and means adjacent the bottom of the spaced guides to locate the platform in position for engagement of the latches by the side bars for raising the platform.

6. A sheet feeder elevator comprising a pair of spaced guides; a side bar guided by each spaced guide; means to elevate the side bars; a platform for supporting a pile of sheets to be raised to feeding level including a pair of spaced channel bars, a plate secured to the flanges at each end of the channel bars forming a latch housing and extending below the channel bar, a pivoted retractile latch carried in each latch housing which retracts by engagement with the descending side bar and thereafter extends to be engaged by the rising side bar to lift the platform and pile of sheets, and a deck carried upon the channel bars; and a pair of upwardly extending flanges adjacent the bottom of the spaced guides and engaged by the plates to locate the platform in two positions prior to engagement of the latches by the side bars for raising the platform.

7. A sheet feeder elevator comprising a pair of spaced guides; a side bar guided by each spaced guide; means to elevate the side bars; a platform for supporting a pile of sheets to be raised to feeding level including a pair of spaced channel bars, a plate secured to the flanges at each end of the channel bars forming a latch housing and extending below the channel bar, a pivoted retractile latch carried in each latch housing which retracts by engagement with the descending side bar and thereafter extends to be engaged by the rising side bar to lift the platform and pile of sheets, and a deck carried upon the channel bars; and a pair of spaced angle irons adjacent the bottom of the spaced guides and each having a flange extending upwardly, the plate resting upon the horizontal flanges thereof and engaging an upwardly extending flange to locate the platform in position prior to engagement of the latches by the side bars for raising the platform.

8. A sheet feeder elevator comprising a pair of spaced vertical guides; a side bar guided by each spaced guide; means to elevate the side bars; a pair of spaced pile guides extending vertically of the elevator and adjustable laterally; a platform for supporting a pile of sheets to be raised to feeding level including a pair of spaced channel bars, a plate secured to the flanges at each end of the channel bars forming a latch housing, a pivoted retractile latch carried in each latch housing which retracts by engagement with the descending side bar and thereafter extends to be engaged by the rising side bar to lift the platform and pile of sheets, and a deck carried upon the channel bars including adjustable members extending outwardly therefrom and between the pile guides; and means adjacent the bottom of

the spaced vertical guides to locate the platform in position for engagement of the latches by the side bars for raising the platform, including a pair of upwardly extending stops spaced a distance apart less than the spacing of the channel bars of the platform so that one stop locates the platform with the adjustable member clear of the pile guides and the other locates the platform with the adjustable members between the pile guides.

9. A sheet feeder elevator comprising a pair of spaced vertical guides; a side bar guided by each spaced guide; means to elevate the side bars; a pair of spaced pile guides extending vertically of the elevator and adjustable laterally; a platform for supporting a pile of sheets to be raised to feeding level including a pair of spaced channel bars, a plate secured to the flanges at each end of the channel bars forming a latch housing and extending below the channel bar, a pivoted retractile latch carried in each latch housing which retracts by engagement with the descending side bar and thereafter extends to be engaged by the rising side bar to lift the platform and pile of sheets, and a deck carried upon the channel bars including adjustable members extending between the pile guides; and a pair of spaced angle irons adjacent the bottom of the spaced vertical guides to locate the platform in position for engagement of the latches by the side bars for raising the platform, one of the flanges of each angle iron extending upwardly and spaced from each other a distance so that one flange is engaged by a pair of plates and serves as a stop for the platform with the angle members clear of the pile guides and the other flange is engaged by another pair of plates and serves as a stop for the platform with the angle members extending between the pile guides.

10. A sheet feeder elevator comprising a pair of spaced vertical guides; a side bar guided by each spaced guide and having a rod extending therebetween and adjacent the rear ends thereof; means to elevate the side bars; a pair of spaced pile guides extending vertically of the elevator and between the spaced guides; a platform for supporting a pile of sheets to be raised to feeding level including pivoted retractile latches carried by the platform which retract by engagement with the descending side bars and thereafter extend to be engaged by the rising side bars to lift the platform and pile of sheets, a deck for supporting the pile of sheets extending between the pile guides, and a roller carried by the platform adapted to engage with the rod extending between the side bars upon tilting of the platform for removal thereof from the elevator.

11. A platform for a sheet feeder elevator having elevating side bars comprising a frame including a pair of spaced cross bars, a latch housing formed at each end of each cross bar, a pivoted retractile latch carried in each latch housing which retracts upon engagement by a descending side bar and thereafter extends to be engaged by the rising side bar, each latch having an inwardly projected extension which engages a stop to retain the same in normal extended position, and a deck carried by the frame.

12. A platform for a sheet feeder elevator having elevating side bars comprising a frame including a pair of spaced channel cross bars, the channel form of cross bar providing flanges, a plate secured to the flanges at each end of the channel bars and forming a latch housing, a pivoted re-

tractile latch carried in each latch housing which retracts upon engagement by a descending side bar and thereafter extend to be engaged by the rising side bars, each latch having an inwardly projected extension which engages a flange to retain the same in extended position, and a deck carried by the frame.

13. A platform for a sheet feeder elevator having elevating side bars, comprising a frame including a pair of spaced channel cross bars, a plate secured to the flanges at each end of the channel bars and forming a latch housing, each plate extending below the channel bar to form a foot, a pivoted retractile latch carried in each latch housing which retracts upon engagement by a descending side bar and thereafter extends to be engaged by the rising side bar, each latch having an inwardly projected extension which engages a flange to retain the same in extended position, and a deck carried by the frame.

14. A platform for a sheet feeder elevator having elevating side bars comprising a frame including a pair of spaced channel cross bars, a plate secured to the flanges at each end of the channel bars and forming a latch housing, a pivoted retractile latch carried in each latch housing which retracts upon engagement by a descending side bar and thereafter extends to be engaged by the rising side bar, each latch having an inwardly projected extension which engages a flange to retain the same in extended position, and a deck carried by the frame.

15. A platform for a sheet feeder elevator having elevating side bars comprising a platform frame including a pair of spaced cross bars, a pivoted retractile latch carried at the end of each cross bar which retracts upon engagement by a descending side bar and thereafter extends to be engaged by the rising side bar, means to retain each latch in extended position, a deck carried by the platform frame, and means carried by the platform frame at one edge thereof to extend the deck and adjustable along the edge thereof.

16. A platform for a sheet feeder elevator having elevating side bars comprising a platform frame including a pair of spaced cross bars, a pivoted retractile latch carried at the end of each cross bar which retracts upon engagement by a descending side bar and thereafter extends to be engaged by the rising side bar, means to retain each latch in extended position, a deck carried by the platform frame, a bar carried by the frame at one edge thereof and spaced from the frame, and angle members inserted within the space between the bar and frame to extend the deck and adjustable along the edge thereof.

17. A sheet feeder elevator comprising a pair of spaced guides, a side bar guided by each spaced guide, means to elevate the side bars, a platform for supporting a pile of sheets to be raised to feeding level, and retractile latches carried by the platform which retract by engagement with the descending side bars and thereafter extend to be engaged by the rising side bars at a point in alignment with the guides to lift the platform and a pile of sheets.

18. A sheet feeder elevator comprising a pair of spaced guides; a side bar guided by each spaced guide, means to elevate the side bars; a platform for supporting a pile of sheets to be raised to feeding level including a pair of spaced channel irons, a plate secured to the flanges at

each end of the channel irons forming a latch housing, a retractile latch carried in each latch housing and normally projecting therefrom which retracts by engagement with the descending side bars and thereafter extends to be engaged by the rising side bars to lift the platform and pile of sheets, and a deck upon the channel irons.

19. A sheet feeder elevator comprising a pair of spaced guides; a side bar guided by each spaced guide; means to elevate the side bars; a platform for supporting a pile of sheets to be raised to feeding level including a pair of spaced channel bars, a plate secured to the flanges at each end of the channel bars forming a latch housing, a pivoted retractile latch carried in each latch housing which retracts by engagement with the descending side bars and thereafter extends to be engaged by the rising side bars to lift the platform and pile of sheets, each latch having an inwardly directed extension which engages the flanges as a stop, and a deck carried upon the channel irons.

20. A sheet feeder elevator comprising a pair of spaced guides, a flat side bar guided by each spaced guide, means to elevate the side bars, a platform for supporting a pile of sheets to be raised to feeding level, retractile latches carried by the platform which retract by engagement with the descending side bars and thereafter extend to be engaged by the upper edge of the rising side bars to lift the platform and a pile of sheets, and means adjacent the bottom of the spaced guides to locate the platform in position for engagement of the latches of the latter by the side bars for raising the platform.

21. A sheet feeder elevator comprising a pair of spaced guides, a flat side bar guided by each spaced guide and having an upper latch

engaging edge in alignment with the guides, means connected with the side bars in alignment with the guides for elevating the same, a platform for supporting a pile of sheets to be raised to feeding level, and retractile latches carried by the platform which retract by engagement with the descending side bars and thereafter extend to be engaged by the upper edge of the rising side bars to lift the platform and a pile of sheets.

22. A sheet feeder elevator comprising a pair of spaced guides, each guide having a pair of guiding edges spaced apart so as to pass a platform therebetween, a side bar guided by each spaced guide, means to elevate the side bars, a platform for supporting a pile of sheets to be raised to feeding level, retractile latches carried by the platform which retract by engagement with the descending side bars and thereafter extend to be engaged by the rising side bars to lift the platform and a pile of sheets, and means adjacent the bottom of the spaced guides to locate the platform in position for engagement of the latches of the latter by the side bars for raising the platform.

23. A sheet feeder elevator comprising a pair of spaced guides, each guide having a pair of guiding edges spaced apart as a whole so as to pass a platform therebetween, a side bar guided by each spaced guide, means to elevate the side bars, a platform for supporting a pile of sheets to be raised to feeding level, and retractile latches carried by the platform which retract by engagement with the descending side bars and thereafter extend to be engaged by the rising side bars to lift the platform and a pile of sheets.
